P. CARTER

OIL BURNER

Filed April 7, 1924

FIG. 1

FIG. 2

Patented Dec. 2, 1924.

1,517,614

UNITED STATES PATENT OFFICE.

PARKE CARTER, OF WICHITA, KANSAS.

OIL BURNER.

Application filed April 7, 1924. Serial No. 704,786.

To all whom it may concern:

Be it known that I, PARKE CARTER, a citizen of the United States, residing in Wichita, county of Sedgwick, and State of 5 Kansas, have invented certain new and useful Improvements in Oil Burners, of which the following is a specification.

My invention relates to oil burners, adapted to burning that quality of oil that 10 can be generated into gas.

The object of my invention is to provide a burner that will store a quantity of oil in close proximity and centrally disposed to the flames, and another object of my invention 15 is to provide a burner having free circulation of air to mix with the gas directly, and also an air supply introduced beneath the exit of the flame, and this supply of air functions to intensify a draft, causing the 20 flames to flow freely from the bowl.

Referring to the drawings, Fig. 1 is an elevation of the burner, part in section, taken on line A, Fig. 2, looking in the direction of the arrow. Fig. 2 is a top view of the 25 burner, parts removed for convenience of illustration.

1 is a bowl functioning as a container for the burner, and generator, and also as a 30 catch basin for the overflow of oil and as a container for a small quantity of oil, as heating and generating purposes when the burner is first lighted; the said bowl has an annular flange 2, concentric to the bowl, said flange extends upward forming a basin to 35 catch the surplus oil as heretofore described, and in said basin is a stud 3 having a hole drilled as shown by dotted lines. The pipe 4 is screwed into the hole functioning as an overflow lead, the said pipe may 40 be connected with a receptacle, or other means of disposing of the surplus oil, or may be connected with an automatic cut off, neither of which are shown in the drawings.

The said flange 2 extending upward as 45 heretofore described, functions as a bearing for the legs 5, said legs are of sufficient length to provide ample opening between the top edge of said flange and vaporizing plate 6; said bowl is of sufficient depth that 50 the flaring top extended above the deflector plate 7 of the burner as shown at B, the object of which is to house the said crown plate in a well heated chamber, and the said bowl being flared, tends to throw the flame 55 outward while the burner is in action. 8 is an air inlet tube having a shoulder threaded

as at 9, and the second shoulder as at 10 for the purpose hereinafter described, the said tube is flaring at the lower end as shown at C, to accommodate for free entering of 60 air, said shell extending upward functions as air conveying means for a thorough mixing of the air and oil vapor, which takes place in a mixing chamber 11.

12 is a sleeve being threaded at one end 65 to engage with threaded shoulder 9 in such a way as to render the joint oil tight, on the opposite end of said sleeve threads are provided to receive the vaporizing plate 6, which is screwed to proper depth so that the 70 end of said sleeve is slightly above the top surface of base plate as shown at D; 13 is an annular cavity between the walls of the wall and sleeve functioning as a reservoir. 14 is a supply pipe entering said reservoir 75 as shown at a convenient place in said pipe is a valve 15 functioning as a stop or means for controlling the flow of oil, said pipe 14 is adapted to connect with fuel oil tank, 80 the tank is not shown in the drawings.

The deflector plate 7 being made of metal, is constructed as shown in section in Fig. 1, the same being conical in shape, and protruding downward as at E, so the apex is 85 below the level of the top of tube 8, by which means, the flow of air is distributed equally to the periphery of the burner. 16 is one of a plurality of legs being integral with the deflector plate, and functions as separating means, forming an aperture 17 90 at the periphery of said vaporizing and deflector plate.

To operate my burner, I place the bowl on a foundation provided in the fire pot of furnace with the shell protruding downward 95 as shown in Fig. 1, connecting a supply pipe as heretofore described, said pipe connecting with a fuel oil tank which is placed at a convenient place, then I turn on the oil which fills the reservoir allowing it to overflow, filling a cavity in plate 6 as shown at F, and from thence overflowing through the aperture, running into the basin of the bowl where it may be lighted for generating purpose, the vaporizing plate being heated will 105 cause accumulated oil in the annular depression F, to be preheated, and while passing from thence over the vaporizing plate. The vapor will mix with the air in chamber 11, and by action of the current through the 110 shell and the gas will pass through the aperture where it will ignite, throwing a large

volume of flames from the bowl it will be understood that the base and crown plate being heated during the action of the burner, the oil in the reservoir will be preheated, 5 causing the generating of the oil into gas, by reason of a quantity of the heated element.

Such modifications may be made as lies within the scope of the appended claims, 10 and what I claim as new and desire to secure by Letters Patent is:—

In a burner of the class described, a bowl having a central opening, a flange surrounding said opening and extending above the 15 bottom of said bowl, a vaporizing plate sup-

ported above said flange forming means for deflecting air passing through said central opening, said vaporizing plate having an axial opening and a depression around said axial opening, a sleeve supported in said axial opening and forming an oil trough with a depression in said plate, an air inlet tube supported at its lower end from said sleeve and spaced therefrom, thereby forming an annular oil reservoir and a deflector 25 supported on and spaced above said vaporizing plate having a conical portion extending within said air inlet tube.

PARKE CARTER.
